HORIZONTAL DRILLING MACHINE

Denzil M. Hollingsworth, St. Louis, Mo.

Application October 26, 1938, Serial No. 236,982

4 Claims. (Cl. 262—7)

My invention relates to a machine adapted for the drilling of horizontal holes in the earth under streets, railroad embankments, or the like, in order to accommodate the laying of pipes for fluids, or to serve as conduits for other purposes. The primary purpose of my invention is to provide a machine which can be quickly set up and dismantled and will be labor saving, safe in operation, inexpensive in cost, operation and upkeep, and speedy in its operation. A further object of the invention is to provide a novel construction which is portable, so that when the drilling operation is completed the drilling mechanism and associated parts may be removed from the pipe, within which said parts have been contained, and carried to another drilling job and quickly set up and ready for use. A still further object of the invention is to provide a cutting blade with projections on the outer face and an inclined scooped-shaped member secured to the inner face thereof for scooping up the loosened earth and dumping the same on an apron and from there onto a travelling conveyor for conveyance to the rear end of the tunnel being drilled. A still further object of the invention is to mount the drilling portion of my machine in the forward conduit section and to apply to the outside end of the conduit section a force sufficient to cause the drill to progress through the earthy material, and at the same time advance the conduit section or sections. A still further object of the invention is to firmly support the drill as well as the flaring apron associated with the drill so that these parts may not be displaced when the machine is operating.

While horizontal drilling machines heretofore have been employed of the same general type as the one herein disclosed, I believe I am the first to show so few parts simply and ruggedly constructed and so arranged as to be quickly and conveniently set up and dismantled and highly efficient in its operation at a minimum expense for labor, maintenance and upkeep.

Fig. 1 is a vertical section of the drilling end of the tunnel.

Fig. 2 is a sectional elevation of the open end of the tunnel showing the pipe-jacking system.

Fig. 3 is an end view of the drilling apparatus.

Fig. 4 is a longitudinal section taken on line 4—4 of Fig. 1.

Fig. 5 is a section taken on line 5—5 of Fig. 1.

Fig. 6 is a vertical section taken on line 6—6 of Fig. 1.

Fig. 7 is a vertical section taken on line 7—7 of Fig. 1.

In the drawings: The earthy material through which the tunnel is drilled is indicated by the letter A, the piping or tubing for lining the tunnel by the letter B. This tubing is preferably of concrete sections, but other material for forming said tubing may be employed and of such diameter as generally used on such jobs. The mechanical conveyor C is of the apron type generally employed to convey material from one point to another. D are the supporting rollers for the conveyor C, and E are the supports for said rollers.

An electric motor (not shown) mounted in a box 10 is connected by cable 11 to a source of electrical power, (not shown), said box 10 is mounted on an angle support 12 extending across the interior of a pipe section B (see Figs. 1 and 7). The motor is connected to a reduction gear in box 10, all of which is of standard construction and no detailed showing of same or a description thereof is believed necessary. A shaft 13 connected to the motor projects from the box 10 and consists of appropriate lengths coupled together as shown at 14.

The shaft 13 is supported near its end where the drilling blade is carried by a member 15 (Figs. 1 and 3) which is hung, as at 16, from the inside top portion of a ring 17, which is mounted in the forward end of the first section of the piping B. The member 15 has a loop 18 which circles the shaft 13, (Fig. 1), to vertically support the same. I preferably employ three screw-threaded centering rods 19 having adjusting screws 20 for maintaining said rods in operative position. The inner ends of the rods 19 abut against the inner forward face of the forward section of the piping B, as shown at 21, while the outer ends abut against a strap 22 which substantially circles the end of the shaft 13. By means of the rods 19 and the member 15 the forward end of the shaft 13 is securely held in fixed operative position within the pipe B.

A series of sweeps 23 is secured to the shaft 13 just to the rear of the strap 22, which sweeps serve to propel rearwardly the earthy material accumulating on the inclined apron 24, located at the forward bottom end of the piping B, and which apron is retained in position by the ring 17 which abuts against an annular projection 25 on the rear face of said apron 24.

A drilling blade 26 is secured to the forward end of the shaft 13 by means of a fastening plate 27 having a collar 28 secured on the outer end of the shaft 13. The blade is bolted to plate 27 by bolts 27'. Teeth 29 are carried by the outer face of the blade 26 and are preferably hooked shaped 55

at their free ends, as shown in Fig. 5 to more effectively disengage the earthy material A against which the rotating blade 26 engages. A shovel-shaped member 30 is secured to the blade 26 near its outer extremity and on the side opposite the face from which the teeth 29 project. The purpose of this member 30 is to cause the earthy material dislodged by the blade 26 to travel up the inclined apron 24 so that such material may be engaged by the sweeps 23 and thus moved rearwardly so as to discharge from the inner end of the apron 24 onto the travelling conveyor C, to be dumped from the opposite end of said conveyor C into any suitable receiving device. A bolt 31 projects from the forward end of the shaft 13 and has rotative engagement with the earthy material somewhat in advance of the rotating blade 26.

In Fig. 2 I illustrate the manner in which the piping B may be pressed forwardly by a jack 32 horizontally disposed against a block 33 pressing against an abutment 34 secured in a stable manner, as against an earthen bank 35, or any other firm medium. The other end of the jack 32 abuts against an L shaped structure 36, which has a stiffening arm 37 secured to the upper and lower extensions of the L-shaped structure 36. These members 32, 33, 34, and 36 are mounted for convenience in moving on a carriage 38. One face of the structure 36 abuts against one end of the piping B, thus forcing, through the action of the jack 32, said piping forwardly, and through the mounting of the drilling mechanism in the forward section of the piping B, keeping such drilling mechanism in firm contact with the earthy material to be removed.

By my simple construction and small number of parts the mechanism may be readily mounted in and disconnected from and removed from the piping B when the tunnel is completed. The ring 17 can, if desired, be made in sections so that it can be readily removed from the forward end of the forward piping section, but this is not essential, as said ring, can be removed without collapsing the same.

By my construction the equipment can be quickly and conveniently applied to and removed from each tunnelling job with a minimum amount of effort.

I claim:

1. A tunnelling machine comprising a motor, a shaft connected to said motor, a drilling blade carried by said shaft, projecting members on the outer face of said drilling blade, means for maintaining said shaft in operative position, an apron mounted adjacent said blade, a ring carried by the forward end of a piping section with which said tunnel is to be lined, said ring abutting against a projection on the outer face of said

apron, a conveyor, and means for causing the material collecting upon said apron to move rearwardly thereon and to discharge therefrom upon said conveyor to be dumped from said conveyor at a desired point. 5

2. A tunnelling machine comprising a motor, a shaft connected to said motor, a drilling blade carried by said shaft, hooked projecting members on the outer face of said drilling blade, means for maintaining said shaft in operative position, an 10 apron mounted adjacent said blade, a ring carried by the forward end of a piping section with which said tunnel is to be lined, a conveyor, and means for causing the material collecting upon said apron to move rearwardly thereon and to 15 discharge therefrom upon said conveyor to be dumped from said conveyor at a desired point.

3. A tunnelling machine comprising a motor, a shaft connected to said motor, a drilling blade carried by said shaft, hooked projecting members 20 on the outer face of said drilling blade, an inclined scooped-shaped member on the inner face of said blade near its outer extremity, an apron mounted adjacent said blade, a ring carried by the forward end of a piping section with which said tunnel is to be lined, said ring abutting against a projection on the outer face of said apron, a member carried by said ring for retaining one end of said shaft in its lowermost vertical position with a series of associated members for holding said shaft in operative position, rotatable sweeps for causing the material collecting upon said apron to move rearwardly thereon and to discharge therefrom upon said conveyor to be dumped from said conveyor at a de- 30 sired point. 35

4. A tunnelling machine comprising a motor, a shaft connected to said motor, a drilling blade carried by said shaft, hooked projecting members on the outer face of said drilling blade, 40 an inclined scooped-shaped member on the inner face of said blade near its outer extremity, an apron mounted adjacent said blade, a ring carried by the forward end of a piping section with which said tunnel is to be lined, said ring abutting against a projection on the outer face of said apron, a member carried by said ring for retaining one end of said shaft in its lowermost vertical position with a series of associated members for holding said shaft in operative position, and rotatable sweeps for causing the material collecting upon said apron to move rearwardly thereon and to discharge therefrom upon said conveyor to be dumped from said conveyor at a desired point and means for forwardly ad- 45 vancing said piping section as the tunnel is drilled. 50 55

DENZIL M. HOLLINGSWORTH.
